[57] CLAIM

The ornamental design for a towel ring fixture, as shown and described.

DESCRIPTION

FIG. 1 is a perspective view of a towel ring fixture showing our new design;

FIG. 2 is a front elevational view thereof;

FIG. 3 is a side elevational view thereof, taken looking from the left of FIG. 2

FIG. 4 is a top plan view thereof; and

FIG. 5 is a bottom plan view thereof.

The shading in the views is intended to represent a metallic reflective surface at the wall mounting end of the mounting bracket contrasted with the transparent surfaces for the remainder of the fixture.
